UNITED STATES PATENT OFFICE.

GEORGE F. CARD, OF COVINGTON, KENTUCKY, ASSIGNOR TO HENRY K. LINDSEY, OF CINCINNATI, OHIO.

GOVERNOR FOR ELECTRO-MAGNETIC BRAKE-CIRCUITS.

SPECIFICATION forming part of Letters Patent No. 369,917, dated September 13, 1887.

Application filed January 17, 1887. Serial No. 224,590. (No model.)

To all whom it may concern:

Be it known that I, GEORGE F. CARD, of Covington, Kenton county, Kentucky, have invented a new and useful Governor for Electro-Magnetic Brake-Circuits, of which the following is a specification.

My invention relates to a device for automatic regulation of the current force in an electro-magnetic brake-operating circuit to correspond with the load of each car or vehicle composing a railway-train.

With the above object in view I provide for each vehicle in the line or circuit a loop or shunt comprising a series of resistances whose automatic inclusion in or exclusion from such shunt-circuit causes variation in the shunt-current, with corresponding but inverse variation in the main or brake-operating current on each respective vehicle.

20 In the accompanying drawings, Figure 1 is an end elevation of a portion of the running-gear of a railway-car provided with my governor. Fig. 2 is a top view of such governor on a larger scale. Fig. 3 represents the same apparatus in the condition it assumes on an empty or nearly empty car. Fig. 4 represents a form of my apparatus for very strong current. Fig. 5 represents its rheostat on a larger scale.

30 All the figures show the resistance-box in section.

A represents a portion of the lower timber or frame of a railway-car truck, and B a portion of its upper timber or frame supported 35 by springs C upon the frame A, so as to be capable of vertical oscillation with respect to it.

D represents a portion of a car-body resting upon timber B and rising and falling therewith. The upward oscillations of timber B 40 are limited by stops b.

E represents a part of that portion of the line of an electro-magnetic circuit which includes the brake-magnets, the position of one of which is indicated diagrammatically by a 45 circle marked "brake-magnet."

e e' are the outgoing and returning lines of a loop or shunt which, leaving the main line at a point on one side of the brake-magnet, joins said line on the other side of said magnet. The line e has permanent metallic contact with a fulcrum, F, that projects from the

side of the timber B. The fulcrum F carries and has electrical communication with a metallic lever, G, whose shorter arm, g, is, by means of a pivot, H, coupled to an arm, J, 55 whose lower end is secured to timber A by means of a pivot, K. A series of holes, g', in the arm g of the lever G permit location of the pivot H nearer to or farther from the fulcrum F. The long arm g" of the lever G carries a spring, L, which presses upon one or other of a series of contact-plates, M, of which plates the lowermost one is wholly insulated, so as to completely rupture the shunt and to compel all the current to traverse the main 65 line whenever the oscillating frame or timber B is so depressed by its superincumbent load as to bring the spring in contact with the said lowermost plate. The other contact-plates communicate consecutively with one another 70 and the uppermost plate with the returnshunt-line e' through a series of resistance-coils, N.

The contact-plates and resistance-coils are preferably protected from dust and violence by a box, O, having a slot, o, for the vertically-oscillating spring L.

I prefer in most cases to use and have here described a rheostat composed of a series of contact-plates and resistance-coils; but in some applications of my governor—as, for example, where very strong currents are employed—I may have recourse to a rheostat of other customary or appropriate construction—such, for instance, as those whose resistance is dependent upon masses of carbon or graphite—85 and of which a form is represented in Figs. 4 and 5, in which U-formed masses R of gas-report carbon take the place of the wire-coils N. The said masses may be embedded in a gangue, S, of any suitable non-conducting substance, 90 such as plaster-of-paris.

It is well known that, compared with a brake-pressure necessary to slow down or stop a heavily-laden car, that requisite for an empty or nearly empty car is very much less. 95 This fact is compensated for in my present invention in the following manner: With an empty or comparatively unloaded condition of the car—such as indicated in Fig. 3—a large portion of the current is shunted around the 100 brake-magnet of that particular car, and the magnet's activity, and consequently the brake

action, is thereby lessened. In a more heavily laden condition of the car—such, for example, as indicated in Fig. 1—additional resistances are included in the shunt, so as to relatively 5 increase the strength of the magnet-circuit by compelling a larger portion of the current to traverse it, and by consequence to secure a more effective brake action. A still further loading of the car, sufficient to bring the spring 10 L in contact with the lowermost contact-plate, operates to completely rupture the shunt and to compel the entire charge to traverse the brake-circuit, accompanied by correspondingly-strong brake action. By this means a 15 number of unequally-loaded portions of a train can be made to stop in the same time, instead of with the customary irregular and injurious action in which the more heavily laden cars crowd forward and butt against the retarded 20 cars in front of them. The width of each contact-plate M coincident with arc of vibrations of the spring L is preferably such that the resistances will not ordinarily be modified by any vertical oscillations of the car incident to 25 slight unevennesses of the track, yet not such but that excessive oscillations will modify the resistances sufficiently on the one hand to insure against brake-pressure, which would be liable to cause "grind" of the wheels along 30 the track, (a liability which is of course in inverse ratio to the car's downstress at any given instant,) and on the other hand to se-

cure vigorous brake-pressure during excessive downstress of such car.

I claim herein as new and of my invention— 35

1. A governor for an electro-magnetic brake-circuit, consisting of a shunt around the brake-magnet, a rheostat included in said shunt, and mechanism whereby the resistance of said rheostat is varied with the load on the car. 40

2. The combination of an electro-magnetic circuit dominating a car-brake, and a shunt to the brake-magnet containing a series of resistances and contact-plates, with a conducting-lever upon the oscillating member of the 45 car-truck, said lever being pivoted to an arm upon the main member of the car-truck, as set forth.

3. The combination, with the magnet-line of an electro-magnetic circuit for car-brakes, 50 of the resistances N, the shunt e e', having communication with said resistances, the contact-plate M, and lever G, having contact-spring L on one member of the truck-frame, said lever being coupled to an arm extending from another member of the truck-frame, with respect to which said first member oscillates, 55 as and for the purposes set forth.

In testimony of which invention I hereunto set my hand.

GEORGE F. CARD.
